UNITED STATES PATENT OFFICE.

WILLIAM E. GREENAWALT, OF DENVER, COLORADO.

ELECTROLYTIC APPARATUS.

1,365,032.

Specification of Letters Patent. Patented Jan. 11, 1921.

Application filed April 29, 1918. Serial No. 231,534.

To all whom it may concern:

Be it known that I, WILLIAM E. GREENAWALT, a citizen of the United States, residing in the city and county of Denver and State of Colorado, have invented certain new and useful Improvements in Electrolytic Apparatus, of which the following is a specification.

This apparatus may be regarded as a modification and a continuation in part of that described in my co-pending applications, Serial No. 16,962, filed March 25, 1915, and Serial No. 145,884, filed February 1, 1917, and represents an improved apparatus for carrying out the processes described in my co-pending process applications, Serial No. 15,583, filed March 15, 1915: Serial No. 140,738, filed Jan. 5, 1917, and Serial No. 185,652, filed August 11, 1917, although it is not intended to limit it to any particular use.

In the electrolysis of impure copper solutions, as for example those obtained from leaching ores with an acid sulfate solution, there is always present iron sulfate, which injuriously affects the operation. Ferrous sulfate in the electrolyte is not particularly harmful, but the ferric sulfate is highly detrimental. The object of this invention is, first, to cause effective deposition of the copper from an electrolyte containing salts of iron; second, to cause effective reduction of the ferric salts formed by the electrolytic action; third, to cause effective oxidation of the ferrous salts and consequent depolarization at the anode.

If a solution of copper sulfate, containing ferrous sulfate is electrolyzed, copper is deposited at the cathode while sulfuric acid and ferric sulfate are produced at the anode, as shown by the following equations:

The ferric sulfate, finding its way to the cathode, combines with the deposited copper, and is again reduced to the ferrous condition, thus:

The loss of efficiency due to this cause is

more or less proportional to the amount of ferric salts in the electrolyte, and under certain conditions may be quite large. In aggravated cases the loss of efficiency may be so great that the copper is dissolved as rapidly as it is deposited.

If, however, the ferric sulfate can be reduced at the expense of a comparatively cheap reducing agent, such as sulfur dioxide, hydrogen sulfide, or copper sulfide, then acid is regenerated, and the iron in the electrolyte, being reduced to the ferrous condition, loses its ability to combine with the deposited copper, as shown by the following equations:

The apparatus will be described more particularly in its application to sulfur dioxide. The effective depolarization of the electrolyte by means of sulfur dioxide depends, first, upon the temperature of the electrolyte, and second, upon agitation. The effective reduction of the ferric compounds in the electrolyte depends principally upon the temperature. On the other hand, sulfur dioxide is only slightly soluble in hot solutions. To effectively harmonize these various conditions, I have devised the apparatus, shown in the accompanying drawings, in which Figure 1, shows a general longitudinal section: Fig. 2, a detail cross section: Fig. 3, a detail longitudinal section: Fig. 4, a detail longitudinal section of electrodes and conductors showing the electrical connections: Figs. 5 and 6, a detail cross section, and a detail longitudinal section, respectively, of a modified apparatus: Fig. 7, a detail plan of Fig. 1, showing the electrodes and electrical connections: Fig. 8, a detail cross section showing the electrodes and electrical connections: Fig. 9, a detail of the rotary spraying device: Fig. 10, a detail of the stuffing box about the electrical conductors: Fig. 11, a detail of the cover of the electrolyzer showing the method of attaching the lead lining to the sheet steel.

In the drawings, 1 is an electrolytic tank, having a removable cover 2, communicating with a gas generator 3, and adapted to contain the electrolyte, and the vertical electrodes 4 and 5, resting on submerged conducting bars 15 and 16 at the bottom of the tank. The electrolyte flows into the tank through the pipe 9, and flows out through the pipe 10. The gas from the gas generator, with which the electrolyte is treated, flows in through pipe 21, and the excess, if any, flows out through pipe 22. Above the electrolyte, and within the hood or cover, is a spraying device, consisting of a shaft 6, rotated in bearings 8, when driven by the motor 11, and having mounted on it disks 7 which are partially immersed in the gas and partially submerged in the electrolyte, and which spray, or atomize, the liquid into the gas confined over it while at the same time submerging some of the gas in the liquid, when rotated at a proper speed by the motor 11.

The electric current is supplied to the electrodes by means of the terminals 24 and 25, and the conducting bars 15 and 16 in the bottom of the tank. Electrical connection is made with the electrodes by letting the electrodes rest on the conducting bars. The electrodes are held in position by the side pieces 17, which may be of wood, and having saw-cuts, or grooves, 18, to receive the ends of the electrodes. In this way the electrodes are firmly secured and maintained parallel. The arrangement for the insulation of the electrodes is shown in Figs. 4, 7, and 8. One end of the electrode rests on its corresponding conducting bar, while the other end rests on an insulation plate. which, in turn, rests on the opposite conducting bar. The electrode 4, for example, rests on the conducting bar 15, making electrical contact therewith, while the other end rests on the insulation plate 19, which in turn, rests on the conducting bar 16. Similarly the electrode 5, rests on the conducting bar 16, making electrical contact therewith, and is insulated from the opposite conducting bar 15, by the insulation plate 20. A current, therefore, entering through the bar 15, and being insulated from the bar 16, would pass through the electrolyte from the electrode 4 to the electrode 5, and then to the conducting bar 16 on which electrode 5 rests and with which it is in electrical contact, while the electrode 4 is insulated from the bar 16. In this way, the total current enters the cell through the bar 15, and passes from all the electrodes 4 to the electrodes 5 through the electrolyte, and out through the bar 16. The conducting bars 15 and 16 are preferably made of copper, with a lead casting 37. The copper gives the desired conductivity, while the lead resists the action of the acids and variable valent salts better

than the copper. The conducting bars are preferably carried through the ends of the cell through stuffing boxes 43; in this way the tank can be kept from leaking, and electrical connection with the conducting bars 70 made outside of the cell. The insertion and removal of the conducting bars is also facilitated in this way. The stuffing box may be made ferro-silicon, copper, or antimonial lead.

The anodes, 4, are held in position by wooden strips 17, which, in turn, are secured to the tank by the pins 48, or possibly, simply by wedges. If desired, for additional security against current leakage, the 80 ends of the anodes 4 may be insulated by the insulation 29, as shown in Fig. 7. In copper deposition there is danger of the copper being deposited in such a way as to make the removal of the cathodes very difficult; to 85 overcome this a special side strip 27, Fig. 7, is arranged with a groove to take the ends of the cathode, and the strip then fitted very loosely to the sides of the tank. The deposited copper will prevent the cathode from 90 sliding in the groove, but when the cathode is removed, the strip 27, which slides easily, will be removed with it, and so all such difficulties are avoided.

The spraying disks 7, are preferably made 95 of rubber or of lead, with serrations 26, and perforation 28, to facilitate the spraying of the liquid into the gas and the submergence of the gas in the liquid. The disks are held in position 100 on the shaft by the washers 12, and the annular rings 38, inserted between the washers, and arranged so that the whole can be made tight and rigid by the screws 39 at the ends of the shaft. If the shaft, or compression 105 rings, are to be protected from the corrosive action of the gas and the electrolyte, it is best done as shown in Fig. 9, by peripheral rings of rubber 36, inserted between the washers 12.

The cover 2, is usually provided with a lead lining 23, to protect the steel cover from the action of the liquids and gases, and also to make the cover tight. The cover is fitted tightly to the lower section of the electrolyzer, and held in position by means of the beams 41, and the rods 42 passing through the side walls of the tank.

It is well known that depolarization is facilitated by heating and by agitating the 120 electrolyte. Steam may be introduced into the cell with the gas, and agitation may be effected by withdrawing a portion of the gas from the cover, or upper section, of the cell above the electrolyte and forcing it into 125 the lower portion of the electrolyte; this not only agitates the electrolyte, but also causes a certain amount of absorption of the gas in the electrolyte, and brings a portion of the gas directly in contact with the elec- 13

trodes. This is shown somewhat in detail in Fig. 2, in which the gas is exhausted from the hood, or cover, 2, through the pipe 32 by means of the exhauster 87 and forced into the distributing pipe 36, and from there distributed to the pipes 33, and into the bottom of the electrolyzer through the perforated pipes 34, where it rises through the electrolyte and agitates it. To accomplish this effectively it is desirable that the exhauster 87 should have a slightly greater suction than that which moves the gas from cell to cell. The pipes 34 have perforations 35 through which the gas is subdivided and more or less uniformly distributed in the electrolyte, and as it rises, it depolarizes the anodes and causes effective oxidation of the ferrous salts. The liquid, containing the ferric salts, then rises, and as it comes toward the top it is caught by the sprayers and the liquid atomized into the reducing atmosphere of the hood where the ferric salts are again reduced, to pass through another cycle of depolarization and oxidation, and this is continued until the electrolyte is sufficiently impoverished in copper and regenerated in acid, when it may be returned to the ore to dissolve more copper.

The general method of attaching the lead lining to the steel cover is shown in Fig. 11, in which 50 shows the steel shell, 23 the lead lining, 53 a bolt by means of which the lead lining is secured to the steel shell, 51 a cap over the bolt head to protect it, and 53 the lead burned ridges which makes a tight and unattackable joint between the lining and the lead cap.

In the modified arrangement of the apparatus, as shown in Figs. 5 and 6, the spraying disks act both as electrodes and as atomizers, and the shaft acts also as a conductor of the electric current. The rotating electrodes give a positive agitation to the electrolyte, and in some cases is to be preferred. The shaft 6 is preferably made hollow (Fig. 9), and a copper bar 45 inserted in the hollow shaft to conduct and distribute the current without too much resistance. Electrical contact with the rotating shaft is made by means of a copper disk 47, rotating in a mercury bath 46. A current with the positive connection at 24 enters the tank through the conductor bars 15, is distributed to the anodes 4, passes through the electrolyte and enters the rotating disk cathodes and sprayers 7, 5, then passes to the shaft as the negative conductor, and out through the copper disk 47 and mercury bath 46.

In operating the process and apparatus the leach solution from the ore, and preferably having its variable valent salts reduced to their lowest valency, is introduced into the electrolyzer 1 through the pipe 9 and is exhausted through the pipe 10. Sulfur di-

and exhausted through the pipe 22 in such a way as to always maintain a slight inward suction to prevent the corrosive gases from escaping from the cell and contaminating the atmosphere. At the same time 70 a portion of the gas over the electrolyte is exhausted from the hood 2 and forced into the lower portion of the electrolyte to agitate it, although this will not always be necessary and in some cases not desirable. 75 The spraying disks are rotated at a high speed, say from 60 to 500 R. P. M. depending on the size of the disks, so that some of the liquid is sprayed, or atomized, into the gas above it while at the same time some 80 of the gas is submerged in the liquid.

When the current is turned on, copper is deposited on the cathodes while sulfuric acid and ferric sulfate are produced at the anode, as set forth in equations 1 and 2. 85 The ferric sulfate finding its way to the cathode immediately attacks the deposited copper, and is itself reduced to the ferrous sulfate, as set forth in equation 3. If this action were to continue indefinitely the 90 process would soon become commercially inoperative. To obviate this, and in order to get a maximum deposition with a minimum of re-solution of the copper, the sulfur dioxide is maintained in excess in the 95 hood above the electrolyte, and as the atomizers spray the electrolyte into the sulfur dioxide gas and submerge some of the gas in the electrolyte, the ferric salt is reduced to the ferrous condition by the sulfur dioxide while at the same time an equivalent of acid is regenerated, as set forth in equation 4. Since the rapidity of this reaction depends considerably on the temperature of the electrolyte, it is desirable to maintain 100 the electrolyte fairly warm, say, at from 120 to 150 deg. F. This may be done by heating the electrolyte before it is introduced into the cell and then maintaining it warm with steam introduced with the gas; 110 or, the gas itself, may be heated. In any event, the electric current will tend to keep the electrolyte fairly warm, but economy may best be served by preheating it.

In order that the electrolyte may be uniformly treated, both in the deposition of the copper and in the reduction by means of sulfur dioxide, the electrolyte is flowed through the cell in a sinuous course, as shown in Fig. 1. This is accomplished by 115 arranging the electrodes to act as baffles, or weirs. The anodes touch the bottom of the cell, while at the upper portion of the cell the anodes are somewhat lower than the cathodes. In this way, the solution introduced through the pipe 9, will flow in a sinuous course to the outlet 10, and at each change of the sinuous flow the liquid comes in contact with the gas and a portion of it is sprayed into the gas, so that the elec- 120 130

trolyte is charged more or less with the gas and the ferric salts more or less reduced as it passes downwardly again to the bottom of the cell. This sinuous flow may not be sufficient to thoroughly depolarize the anodes, which is best done with more or less agitation, especially if high current densities are used. To accomplish this, a portion of the gas is exhausted from the hood and forced into the lower portion of the electrolyte, as already described. It is not impossible to use air for this agitation, but the gas, itself, is preferred, for if air is used the volume of the gas is increased and the gas diluted, whereas if the gas is used no dilution or increase in volume takes place.

It is very desirable to always maintain the sulfur dioxid in excess in the cell. This excess should be as great as can conveniently be maintained. Fortunately this can readily be done, as sulfid ores are almost always available, and the sulfur dioxid from roasting is otherwise usually a waste product. With a hot or a warm electrolyte the space in the electrolyzer above the liquid will contain much of the liquid sprayed into it, as a fine mist and steam, and thus the reactions between the gases and liquid is rapidly effected.

In electrolyzing solutions by the method and apparatus here proposed, it is evident that the usual electrical connections will not suffice. In the swirl of the gases and electrolyte the usual electrical connections with the electrodes would be too complicated and would be very quickly corroded, and on account of the difficulties of getting at such connections, the practicability of the apparatus might be questioned. These difficulties are overcome by having two conducting bars in the bottom of the tank; one for the positive and one for the negative conductor. The electrodes rest on these conducting bars and their weight suffices to make the proper contact for the electric current. The edges of the cathodes are insulated from the anode bar, and the edges of the anodes are insulated from the cathode bar. The anodes may be either lead, carbon, or magnetite, or ferro silicon, and the cathodes either lead or copper.

Depolarization, when using lead anodes is not as complete as when using carbon anodes. Lead anodes have the advantage that they can be made in any reasonable size, while carbon anodes will have to be composed of a number of individual slabs, as shown in Fig. 2. Carbon anodes will not last well unless depolarization is quite complete, and this depolarization is made effective by carrying a high percentage of iron in the electrolyte, and using the ferrous salt as a depolarizer, while at the same time agitating the electrolyte to bring the fer-

rous salt in intimate contact with the anode. In this way the E. M. F. required for electro-deposition is materially reduced. Large carbon electrodes are necessarily made of slabs, but there is difficulty in assembling the slabs to get good electrical conductivity. I overcome this difficulty entirely by laying the first slab on the conductor bars with one end properly insulated from the cathode conductor bar, and by means of wooden grooved pieces at the sides, lay one slab vertically on top of the other with the adjacent edges contacting, as shown in Fig. 2. In this way the electrode may be built vertically as large as desired, while the electrical contact between the slabs is all that is necessary. If perfecting abutting edges are desired to give a better electrical contact, the abutting edges may be planed to a true surface. This will not ordinarily be necessary, for, even if the contact in the beginning is not perfect, it will soon be made so by the electrolytic action of the current in depositing copper between the gaps.

It might be thought that the covered electrolyzers would complicate the electrolysis and increase the cost of operation. It is more likely to simplify the operation and cheapen the cost of deposition. The idea, of course, is, to use fairly large units, and while the cost of the individual cells is greatly increased, the cost of the electrolytic installation, as a whole, is materially diminished. Electrolytic dynamos with a capacity of 10,000 amperes at 12 volts are regularly made as a standard size; if a larger current is desired two of these machines may be used in multiple, thus giving 20,000 amperes at 12 volts. Carbon electrodes are regularly made in slabs of 50x8x2 inches, from which an electrode 50x72 inches in area could readily be constructed as described, and having a total active area of approximately 50 square feet. With a current density of 15 amperes per square foot, each electrode would take 750 amperes, and with 30 cathodes and 31 anodes there would be a total current of the 20,000 amperes. This cell would require an approximate floor space of 6x18 feet.

Assuming a current efficiency, under the conditions, of about 96 per cent., or 2.5 lbs. of copper from cupric solutions, per 1000 ampere-hours, there would be deposited 50 lbs. of copper per hour with 20,000 amperes, or 1200 lbs., per day of 24 hours, per cell. If the deposit on each side of the cathode is a quarter inch thick, the total weight of the copper on each cathode would be approximately 1155 lbs., and for 30 cathodes 34,650 lbs. Depositing at the rate of 1200 lbs. per day, approximately 26 days would be required to make this deposit. Or in other words, the cell would not have to be disturbed or the cover lifted for a period

of from 26 days to a month, when it would be cut out of circuit and from 34,650 to 41,000 lbs. of copper, approximately, removed therefrom. It is true that trees may 5 form, but with a low current density and adequate circulation and agitation of the electrolyte, this is not likely to cause trouble for a deposit approximately $\frac{1}{4}$ inch thick.

10 There is no difficulty in removing the cover from the cells. The cells are easily arranged so that they can be disconnected, one at a time, and a traveling crane used to lift the cover and place it on a fresh cell, 15 while the one from which the cover was taken has its copper removed. In taking the copper out of the cells, the individual cathodes are lifted out with pincers suspended from the crane. If lead or thick copper 20 cathodes are used, the deposited copper is easily pried off, and the cathode returned to the cell. The anode is not removed until worn out.

In the operation of these cells it is unnecessary to resort to expensive absorption towers and an elaborate system of pumping and circulation. All this may be eliminated. Manifestly if the variable valent salts can be reduced by sulfur dioxid at all, they can 30 always be maintained reduced under the action of this cell, practically speaking, especially at fairly high temperatures, say from 120 to 150 degrees F. It will not be necessary to pass the electrolyte through 35 more than one cell, although in large plants it is preferred to pass it through two, and possibly three, in series, with different current densities. In which case the gas, as well as the electrolyte, is passed success- 40 sively through a series of cells, the richer electrolyte and the richer gas being preferably introduced into the first cell of the series. The current density in the succeeding cells is preferably diminished in proportion as the electrolyte becomes impoverished in copper, and the most suitable current density can only be determined by experiment; it will usually vary from 10 to 5 amperes per square foot.

50 It is well known that the E. M. F. required in copper deposition from solutions containing considerable ferrous sulfate, is greatly reduced on account of the depolarization at the anodes. The difficulty hitherto has been to practically maintain the iron in the ferrous condition, for, depolarization is effected by the ferrous salts being oxidized, or adduced, to the ferric condition, and if the reduction to the ferrous salts is 55 promptly made, the advantages gained by the reduced E. M. F. due to depolarization, greatly outweighs the disadvantages due to the corrosive action of the small amount of ferric salts which unavoidably exists in the 60 electrolyte. At fairly high temperatures

sulfur dioxid is quite active in reducing the ferric salts; on the other hand, the gas is not as soluble in a heated electrolyte. But, as the object is, not so much to absorb large quantities of the gas as to maintain the ferric salts reduced, the solubility of the gas, as used in this apparatus, is not a matter of much consequence. With the comparatively perfect depolarization possible in this cell the E. M. F. should not exceed 1.5 volts. 70 Under these conditions an electrolytic dynamo of 20,000 amperes and 12 volts would deposit 9600 lbs. of copper per day of 24 hours, with eight cells.

The gas, as well as the electrolyte is pref- 80 erably given a sinuous flow through the cell, by the arrangement of baffles, as shown by 30 and 31. These baffles not only give the gas a sinuous flow through the cell, but also offer a largely increased surface for treat- 85 ing the gas with the electrolyte. The gas comes intimately in contact with the film of liquid on the surface, and as the film becomes charged with the gas, the spraying of fresh liquid into the gas washes it down and 90 exposes fresh liquid on the surface. Similarly, with the rotating disks; if the disks, for example, have an area of 5 sq. feet, and rotate at 60 R. P. M., there will be 1800 sq. feet of surface exposed both to the liquid 95 and the gas, per minute, and if there are 20 disks in a cell, the total exposure would be 36,000 sq. feet of fresh surface per minute. This, in addition to the spray, or atomized liquid, filling the hood, is believed to give 100 the most effective treatment possible for electrolytic work involving the treatment of the electrolyte with the gas.

Circulation of the electrolyte may also be desirable. This is effectively accomplished by conducting the sprayed and charged liquid in the upper portion of the apparatus, through the ducts 55, (Fig. 2) to the lower portion of the tank. It may circulate with or without the gas leading to 110 the gas distributing pipe 34.

The apparatus may be used for various purposes, as for example, the treatment of ores by chlorination, the precipitation of metals from either acid or alkaline solutions, the manufacture of sulfuric acid, and the purification of water. It may be used for oxidizing as well as reducing reactions. In the electrolysis of a substance involving the liberation of a gas, the excess gas lib- 115 erated by the electrolytic action rises to the surface, and may be effectively absorbed by the spraying device in the hood. The slight modifications required, if any, to adapt the apparatus to various uses, will readily suggest themselves to any one skilled in the art.

If carbon, magnetite, or ferro-silicon anodes are used, the size of the cell will be limited by the size of the anode slabs. If, however, lead anodes, and lead or copper 130

cathodes, are used, the size of the cells may be greatly increased. Electrodes 10x10 feet x $\frac{1}{2}$ inch thick, in a cell 18 feet long, would seem quite reasonable for practical construction and operation. Such a cell would take 100,000 amperes, at 10 amperes per square foot, and should deposit from 5000 to 6000 pounds of copper per day of 24 hours. The cost of such cells would be rather high, but 10 the cost of the electrolytic installation, as a whole, would be comparatively low. It would be much less than with the small or moderate sized cells at present used.

The end strips 27, Fig. 7, may be attached 15 to the electrode 5 by drilling a hole through the strip and into the edge of the electrode, and then fastening the strip to the electrode by means of a lead or wooden pin 50, which is unaffected by the electrolyte, and can be 20 replaced as desired.

I claim:

1. In electrolytic apparatus a chamber having a gas inlet and a gas outlet and a liquid inlet and a liquid outlet and adapted 25 to contain a liquid and to confine a gas over the liquid, electrodes within said chamber arranged to give the electrolytic a sinuous flow from the inlet toward the outlet, means for charging the electrolytic with the gas 30 confined over it, and means for electrolyzing the liquid.

2. In electrolytic apparatus a chamber having a gas inlet and a gas outlet and a liquid inlet and a liquid outlet and adapted 35 to contain a liquid and to confine a gas over the liquid, electrodes within said chamber arranged to give the electrolyte a sinuous flow from the inlet toward the outlet, means for electrolyzing the liquid, and means at 40 the crests of the sinuous flow to bring the liquid in contact with the gas.

3. In electrolytic apparatus a chamber having a gas inlet and a gas outlet and a liquid inlet and a liquid outlet and adapted 45 to contain a liquid and to confine a gas over the liquid, electrodes within said chamber arranged to give the electrolyte a sinuous flow from the liquid inlet toward the outlet, means for electrolyzing the liquid, and 50 means at the crests of the sinuous flow for spraying the liquid into the gas.

4. In electrolytic apparatus a chamber having a gas inlet and a gas outlet and a liquid inlet and a liquid outlet and adapted 55 to contain a liquid and to confine a gas over the liquid, means within said chamber for giving the liquid a sinuous flow from the liquid inlet toward the outlet, means for electrolyzing the liquid, and means for intimately mixing the gas and the liquid at 60 the crests of the sinuous flow.

5. In electrolytic apparatus, a tank having conductor bars for the electrodes submerged in the electrolyte with removable

electrodes resting thereon, means at the sides 65 of the tank through which the conductor bars may be removed and replaced.

6. In electrolytic apparatus a tank having the conductor bars for the electrodes submerged in the electrolyte, means at the 70 sides of the tank through which the conductor bars may be removed and replaced, and means arranged for making the electrical connections with the conductor bars on the extension of the bars outside of the apparatus. 75

7. In electrolytic apparatus having submerged conductor bars, electrodes composed of superimposed sections with the lower section resting on the conductor bar. 80

8. In electrolytic apparatus having submerged conductor bars, electrodes composed of superimposed sections with the lower section resting on the conductor bars and the remaining sections making electrical 85 connection through abutting edges and the contact originally due to their weight.

9. In electrolytic apparatus arranged to confine a gas over the electrolyte, conducting bars in the bottom of the electrolyzer 90 and electrodes composed of superimposed sections resting on the conductor bars said sections making electrical contact from one to the other through abutting edges and the weight of the electrodes. 95

10. In electrolytic apparatus, a lower section adapted to contain a liquid, a removable upper section engaging the lower section and adapted to confine a gas, electrical conductors submerged in the electrolyte in 100 the lower section, and electrodes resting on the submerged conductors and making electrical contact therewith.

11. In electrolytic apparatus with conductor bars for distributing the electric current to the electrodes submerged in the electrolyte, conductor bars made of copper to give the necessary conductivity and protected by a casing capable of resisting the corrosive action of the electrolyte. 105

12. In electrolytic apparatus a chamber adapted to contain a liquid and to confine a gas over the liquid, means within said chamber for charging the liquid with the gas over it, means for electrolyzing the 115 liquid, and means for withdrawing a portion of the gas from above the electrolyte and introducing it into the lower portion. 110

13. In electrolytic apparatus, a lower section adapted to contain a liquid, a removable upper section engaging the lower section and forming a sealed chamber therewith and adapted to confine a gas over the liquid, electrical conductors submerged in the electrolyte in the lower section, removable stationary electrodes resting on the submerged conductors, means for passing an electric current through the conductors and 125

- the electrodes, and means for withdrawing a portion of the gas in the upper section and forcing it through the liquid in the lower section.
- 5 14. In electrolytic apparatus having pipes for distributing a gas in the electrolyte, pipes arranged in parallel series under the electrodes with the ends projecting through the sides of the tank, means in connection 10 with the pipes for preventing the escape of the liquid, a common main connecting the series of pipes, and means outside of the apparatus for connecting and disconnecting the pipes and the main without disturbing 15 the distributing pipes in the tank.
15. In electrolytic apparatus, a chamber adapted to contain a liquid and to confine a gas over the liquid and having a gas inlet and a gas outlet and a liquid inlet and a 20 liquid outlet, means for causing a flow of liquid through the chamber, means for causing a flow of gas through the chamber over the liquid, means for withdrawing a portion of the gas from above the liquid and introducing 25 it into the liquid below the electrodes through a permeable surface so that the gas will ascend through the liquid in a subdivided condition, and means for electrolyzing the liquid.
- 30 16. An electrolytic apparatus having pipes for distributing a gas submerged in the electrolyte, said pipes being arranged in parallel series under the electrodes and parallel therewith.
- 35 17. In electrolytic apparatus, a chamber adapted to contain a liquid and to confine a gas over the liquid, means for withdrawing a portion of the gas from above the surface of the liquid and introducing it into 40 the liquid below the electrodes through a permeable surface adapted to subdivide the gas, and means for electrolyzing the liquid with the subdivided gas ascending through it.
- 45 18. In electrolytic apparatus having a gas inlet and a gas outlet and a liquid inlet and a liquid outlet and adapted to contain a liquid and to confine a gas over the liquid, means for maintaining a flow of gas from the 50 gas inlet toward the gas outlet with a slight suction inwardly, means having a greater suction for withdrawing a portion of the gas from the stream and injecting it into the lower portion of the electrolyte and 55 means for electrolyzing the liquid.
19. In electrolytic apparatus having a gas inlet and a gas outlet and a liquid inlet and a liquid outlet and adapted to contain a liquid and to confine a gas over the 60 liquid, electrodes arranged to cause the electrolyte to flow from the inlet toward the outlet in a, sinuous stream, and means for injecting a gas into the lower portion of the electrolyte.
20. In electrolytic apparatus having electrical conductors submerged in the electrolyte and electrodes resting thereon, strips at the ends of the electrodes to hold the electrodes in position and loosely arranged within the electrolyte tank so that they may 65 be removed with the electrodes.
21. In electrolytic apparatus, a lower section adapted to contain the electrolyte and the electrodes, an upper section engaging the lower section and forming a sealed 70 chamber therewith, means for introducing a gas in the upper section, means for spraying the electrolyte in the lower section into the gas in the upper section, and baffles arranged in the upper section for giving the 75 gas a sinuous flow through the chamber.
22. In electrolytic apparatus having submerged conductor bars of both polarities, anodes composed of superimposed sections making electrical contact through abutting 80 edges, and arranged so that the lower section is in electrical contact with the anode conductor bar and electrically insulated from the cathode conductor bar.
23. In electrolytic apparatus, a tank 85 adapted to contain the electrolyte, electrical conductors submerged in the electrolyte, removable stationary electrodes within the tank arranged so that electrical contact between the conductor and electrodes is made 90 below the surface of the electrolyte, and means for passing an electric current through the conductors and the electrodes.
24. In electrolytic apparatus having conductor bars submerged in the electrolyte 100 and removable electrodes resting thereon, means at the sides of the tank for maintaining the electrodes in a vertical position, and means along the edges of the electrodes for insulating the electrodes of one polarity 105 from the electrodes of the opposite polarity.
25. In electrolytic apparatus having the edges of the electrodes protected with insulation strips, holes arranged along the edges of the electrodes, and pins in connection with said holes for fastening the insulation strips to the edges of the electrodes. 110
26. In electrolytic apparatus having electrical conductors submerged in the electrolyte and electrodes composed of superimposed sections resting thereon, supporting strips at the sides of the electrolyte tank arranged with grooves to receive the electrode section and maintain the electrodes in position. 115
27. In electrolytic apparatus, a chamber adapted to contain a liquid and to confine a gas over the liquid and having a gas inlet and a gas outlet and a liquid inlet and a liquid outlet, means for causing a flow of liquid through the chamber, means for causing a flow of gas through the chamber over the liquid, means for withdrawing a portion 120
- 125

of the gas from above the surface of the liquid and introducing it below the surface of the liquid through a permeable surface adapted for subdividing the gas, and means 5 for electrolyzing the liquid.

28. In electrolytic apparatus, anodes composed of horizontally disposed superimposed sectional components with the lower section resting on an electrical conductor

submerged in the electrolyte and making 10 electrical contact therewith and arranged so that the sectional components make electrical contact with one another through their respective horizontal abutting edges.
